William Williams Attorney.

UNITED STATES PATENT OFFICE.

ARVID EK, OF PORTLAND, MAINE, ASSIGNOR TO BROWN COMPANY, OF PORTLAND,
MAINE, A CORPORATION OF MAINE

DISPENSING CABINET.

Application filed April 28, 1920. Serial No. 377,261.

To all whom it may concern:

Be it known that I, ARVID EK, a citizen of the United States, residing at Portland, in the county of Cumberland and State of Maine, have invented certain new and useful Improvements in Dispensing Cabinets, of which the following is a specification, reference being had therein to the accompanying drawing.

10 My invention relates to dispensing cabinets and more particularly to a cabinet for dispensing paper towels.

The invention has for its principal object the provision of a cabinet to contain a number of folded towels and means for dispensing one towel at a time from the bottom of the cabinet.

Another object resides in constructing the lower end of the cabinet in such a manner 20 that a portion of one towel will project therefrom in position to be easily grasped and removed.

A further object resides in the provision of means for opening the front of the cabinet 25 to put in a new supply of towels, and means for supporting the front in a horizontal position when open.

With these and other objects in view, my invention consists in the novel details of 30 construction and arrangement of parts which will be more clearly understood from the following specification and drawings, in which:—

Figure 1 is a side elevation.

35 Figure 2 is a similar view with parts shown in section.

Figure 3 is a bottom plan.

Figure 4 is a sectional view on the line 4—4 of Figure 2, looking in the direction 40 of the arrows.

Figure 5 is a vertical section with the front lowered.

In the drawings, 1 indicates the back of the cabinet having a top flange 2, side flanges 3, and a bottom flange 4. This bottom flange 4 is inclined downwardly and the edge is rolled to form a bead 5 for a purpose to be later described. A downwardly extending lip or projection 6 is formed on the top flange 2, intermediate the ends, and will be used for a purpose as will later appear. The back 1 may be secured to the wall or other support in any desired manner but I preferably provide openings therein through

which screws or other suitable fastening means may pass.

A front or cover is hingedly connected to the back and comprises a front plate 7, top 8, sides 9, and bottom 10. The bottom 10 is inclined and the edge is rolled to form a bead 11. This bead 11 will be spaced from the bead 5 so as to leave an opening through which a towel may be withdrawn. The ends of the bottom 10 are bent upwardly at right angles as shown at 12, to engage the inner faces of the sides 9 and are secured to the sides by means of rivets 13. The sides 9 are provided on their lower ends with extensions 14 and one of the sides 9 is provided with a plurality of openings 15 which, if desired, may be covered with glass or other transparent material.

The downwardly extending flange 4, on the back, with the downwardly extending bottom 10 of the cover, forms a hopper for supporting the towels, indicated at 16.

A weight 17 will be carried on the top of the towels to act as a follower for feeding the towels to the bottom of the cabinet as they are used. A rod 18 will pass through the bead 5 of the back, and sides 9 of the front to hingedly connect the front to the back.

The plate 19 is secured to each extension 14, of each side, by means of rivets 20 or other suitable fastening means and these plates are provided with right-angled extensions 21 which, as shown, extend at an angle in such a position as to engage the flange 4 of the back, when the front or cover is lowered, to hold the cover in horizontal position.

A housing 22 is secured to the under side of the top 8 of the front, adjacent the forward edge, and a latch 23 is pivotally connected in the housing beneath the top. This latch is adapted to engage the lip or projection 6 when the front is raised. An opening is formed in the top 8, adjacent the latch, to receive a key for operating the latch.

From the above detailed description, it is thought that the construction and operation will be clearly understood. To fill the cabinet, the latch 23 is operated to release the front so that it may be lowered into horizontal position. When in horizontal position the extensions 21 on the plates 19 will engage the flange 4 and securely hold the

front in such position. When in this position, the towels will be placed in the front or cover and as shown, the towels are folded so that the ends of adjacent towels interlock with one another so that when a towel is withdrawn it will bring an edge of the next towel through the bottom opening to be in position to be grasped for removal. The weight or follower 17 is then placed in position and the front raised and locked in position by the latch 23. As previously stated, the inclined flange 4 and inclined bottom 10 make a hopper-shaped or concaved bottom with an opening between the edges of said flange 4 and bottom 10. This hopper-shaped or concaved bottom will so hold the towels as to direct the edge of the towel through the opening. The lower towels will be slightly curved, as shown. I lay particular stress on the shape of the bottom of the cabinet as well as the means for supporting the lowered front in horizontal position.

The cabinet will preferably be constructed of sheet metal, although any other suitable material might equally as well be used, and while I have described the preferred embodiment of my invention, it will be understood that slight changes might be made in the construction and operation without departing from the spirit of the invention.

Having fully described my invention, what I claim as new and desire to secure by Letters Patent is:—

A dispensing cabinet comprising a back section having a rear wall, vertical sides, and an inclined bottom, the forward longitudinal edge of the bottom being rolled to form an eye, a front section having a front wall, vertical sides, and an inclined bottom, the forward longitudinal edge of the bottom being rolled and spaced from the rolled edge of the bottom of the back section to form a discharge opening therebetween, means passing through the sides of the front section and the eye of the bottom of the back section for pivotally connecting the sections adjacent their lower ends, extensions formed on the sides of the front section, in front of the rolled edge of the bottom and extending therebelow to form closures for the ends of the discharge opening, and means carried by the extensions and engageable with the bottom of the back section for limiting the downward swinging movement of the front section with respect to the back section.

In testimony whereof I hereunto affix my signature in the presence of two witnesses.

ARVID EK.
